UNITED STATES PATENT OFFICE

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT

SUITCASE LOCK

Application filed May 23, 1931. Serial No. 539,511.

My invention relates to devices for retaining covers of suit cases or other receptacles in closed positions and an object of my invention, among others, is to provide a device of this character that shall be simple in construction as well as simple and effective in operation, and one that shall present an extremely slight appearance.

One form of a suit case lock embodying my invention and in the construction and use of which the objects herein set out, as well as others, may be attained is illustrated in the accompanying drawing, in which—

Figure 1 is a face view of a suit case lock and hasp embodying my invention.

Figure 2 is a edge view of the same shown as applied to a suit case or similar receptacle.

Figure 3 is a view in lengthwise section through my improved lock and hasp.

Figure 4 is a similar view through the lock illustrating the manner of holding the catch in its retracted position.

Figure 5 is a rear face view of the lock and hasp.

Figure 6 is a view similar to Figure 5 but with the hasp and back plate of the catch and the tumbler removed as denoted by the dotted line 6—6 of Figure 3.

Figure 7 is a view of a fragment of the lock plate looking from the rear.

Figure 8 is a front view illustrating a little different arrangement.

In the accompanying drawing the numeral 8 illustrates a suit case and 9 the cover thereof which parts may be of any ordinary and well-known construction. A hasp plate 10 is secured to the cover in any suitable manner and a hasp 11 is pivotally attached to the hasp plate, said hasp having a spring 12 for forcing it to an open position. The hasp is preferably of box form, that is, it is closed in on its front end and opposite sides, and the front end is provided with a releasing lip 13 to be herein-after referred to.

A lock plate 14 is secured to the suit case 8 in any suitable manner, this plate having a bounding flange 15 enclosing a space back of the plate and between it and the suitcase.

A sliding catch 16 is mounted on the face of the plate 14, said catch being of the closed-in type, that is, with its sides and ends provided with flanges that rest against or in proximity to the face of the plate 14. A rib 17 is formed on the end of the catch to provide an operating thumb or finger piece.

A back plate 18 is secured to the catch 16, as by means of lugs 19 positioned between clips 20 projecting from the back or bottom edges of the sides of the sliding catch. A retaining plate 21 is secured to the catch 16 as by means of holes that receive the clips 20 which are bent over to secure the parts in position, the retaining plate, when the parts are assembled, being located on the opposite side of the lock plate 14 from the back plate 18, the parts being secured in such manner as to afford free sliding action of the catch and back including the retaining plates relatively to the lock plate 14. The retaining plate is located in the space within the bounding flange on the lock plate herein-before referred to.

The retaining plate 21 has one edge 22 insertable between a catch holder 23 and the back of the lock plate 14 when the catch is in its closed position, the holder 23 being in the form of a spring secured to the back face of the lock plate and having a retaining lip 24 positioned to engage the edge of the retaining plate when the catch is in its releasing position thereby to retain the catch disengaged from the hasp. The releasing lip 13 on the hasp hereinbefore referred to is adapted to pass through an opening 25 in the lock plate and to engage the holder 23 to spring the latter backwardly to release the retaining lip 24 from the edge of the retaining plate 21, and when thus released, the retaining plate is forced toward the hasp and into the position shown in Figure 3 as by means of a spring 26 located between a stop 27 upturned from an edge of the opening 28 through the lock plate and a lug 29 outturned from the edge of a notch 30 in the back plate 18. The stop 27 engages the wall of a recess 31 formed in the catch underneath the rib 17 to limit the engaging movement of said catch, and movement of said catch in the opposite

direction is limited by engagement of the prongs or clips 20 with the edge of the opening 28 in the lock plate.

The catch 16 has a keeper formed by cutting away the under edge of the nose 32 of said catch to provide a space between said nose and the lock plate into which the end of the hasp 11 projects when the parts are in engaging positions and as shown in Figure 3 of the drawing.

In operation it will be noted that when the catch 16 is retracted as by pressure of the thumb or finger upon the rib 17 the nose 32 will be disengaged from the end of the hasp 11 and the spring 12 will immediately throw the hasp to its open position as shown in dotted lines in Figure 2. When the hasp is thus moved back the holder 23 springs to a position in front of the retaining plate 21, thereby holding the catch in its retracted position. When the hasp 11 is pressed into its closed position, as shown in Figure 3, the lip 13 on the catch engages the holder 23 forcing it backwardly and thereby releasing the retaining plate 21, which being secured to the back plate 18 and the latter being secured to the catch, the latter is forced to its holding position by means of the spring 26 which presses against the plate 18.

In order to lock the catch in its closed position I provide a bolt 33 slidably mounted between guides 34 projecting from the retaining plate 21, said bolt being located within the opening 28 in the lock plate and being frictionally held by a spring 35, a notch 36 in the bolt being engaged with one of the guides 34 and as shown in dotted lines in Figure 5 of the drawing. An actuating notch 37 in a side edge of the bolt is adapted to be engaged by the bit of a key inserted through a key hole 38 in the catch 16 whereby the bolt may be released from engagement with the guide 34 and moved backwardly and disengaged from a locking prong 39 extending from the front edge of the opening 28 in the lock plate 14. When the locking bolt has its end located opposite the end of said locking prong the catch is locked against movement, and a key inserted in the key hole 38 will be required to move the bolt to its unlocking position to permit movement of the catch.

In the structure shown in Figure 8 the plate 14, the hasp 11 and its supporting plate 58 are substantially the same as hereinbefore described with respect to the preceding figures, the difference being that the sliding catch 16 is mounted to slide lengthwise of the plate 14 instead of crosswise thereof and said catch engages a side edge of the hasp 11 instead of the end thereof.

In accordance with the provisions of the patent statutes I have described the principles of operation of my invention together with the device which I now consider to

represent the best embodiment thereof; but I desire to have it understood that the device shown is only illustrative, and that the invention may be carried out by other means and applied to uses other than those above set out.

I claim:

1. A lock including a pivotally mounted hasp, a lock plate, a catch slidably mounted on the outer face of said plate to engage and hold said hasp in its closed position, means attached to the back of said plate and adaptable for engagement with said catch for retaining it in its disengaged position, and means on said hasp to engage said retaining means through said plate to release it from said catch.

2. A lock including a lock plate having an opening therein, a catch slidably engaged with the outer face of said plate, a retaining plate engaged with the opposite face of said lock plate, means extending through said lock plate to secure said catch and retaining plates together; a hasp engageable with said catch by sliding movement of the latter to secure the hasp in its closed position, and means within the catch for locking it in its closed position.

3. A lock including a lock plate having an opening therein, a catch slidably engaged with one face of said plate, a retaining plate engaged with the opposite face of said plate, means extending through said lock plate to secure said catch and retaining plates together, means to engage said retaining plate to hold said catch in unlocked position, a hasp engageable with said catch to secure the hasp in its closed position, and means engageable by said hasp for releasing said retaining plate to permit movement of said catch.

4. A lock including a lock plate having an opening therein, a catch mounted on the front face of said plate, a back plate secured to said catch and slidably engaged with the front face of said lock plate, a retaining plate slidably mounted on the back face of said lock plate, means uniting said catch and retaining plates through said lock plate, means engaged with said back plate to force the catch into closed position, a holder engageable with said retaining plate to hold the catch in its open position, a hasp engageable with said catch to hold the hasp in its closed position, and means on said hasp to engage said holder to release said catch.

5. A lock including a lock plate having an opening therein, a catch having a recess in its rear side with lugs projecting from opposite edges of said recess, a back plate extending across said recess and having projections located between said lugs, said back plate being slidably mounted on the front face of said lock plate, a retaining plate in sliding contact with the back face of the lock plate

and secured in place by said lugs, and a pivotally mounted hasp engageable with said catch to secure the hasp in locked position.

6. A lock including a lock plate having an opening therein, a catch having a recess therein, a back plate carried by said catch and extending across said recess in slidable engagement with the front face of said lock plate, a retaining plate secured to the catch in slidable engagement with the back face of the lock plate, locking mechanism including a locking bolt mounted in the opening in the lock plate and between said back and retaining plates, and a hasp engageable with said catch to hold the hasp in its locked position.
